UNITED STATES PATENT OFFICE.

SIGMUND F. KOHN, OF NEW YORK, N. Y.

IRONING-BOARD COVER.

Application filed March 28, 1925. Serial No. 19,033.

To all whom it may concern:

Be it known that I, SIGMUND F. KOHN, a citizen of the United States, and resident of New York city, in the county of the Bronx and State of New York, have invented certain new and useful Improvements in Ironing-Board Covers, of which the following is a full, clear, and exact description.

10 Among the principal objects which the present invention has in view are: to provide a reversible cover for ironing boards; to provide means for quick attachment of a cover over an ironing board; to provide 15 means in a cover for imparting a transverse tension thereto across an ironing board; and generally to provide a novel and improved form of cover cloth for ironing boards.

Drawings.

Figure 1 is a bottom plan view of a cover as applied over an ironing board.

Figure 2 is a longitudinal section through a board with a cover mounted thereover.

25 Figure 3 is a side elevation showing the cover, with pocket portions thereof, inverted from the form as in Figs. 1 and 2.

Description.

30 In the preferred embodiment of the invention, the cover is formed from a strip or body of heavy cloth 10 shaped to conform to the configuration of the conventional ironing board 11, over one face of which it is adapted to be stretched when in service 35 position.

Stitched to the large end of the cover, is a pocket 12 formed of a cloth portion having its inner end 13 open and formed to slip 40 over the ironing board end to envelop the board end up to the straight side edge of the board. At the opposite end of the cover is stitched another pocket portion, to envelop the smaller end of the board, but at this 45 point the pocket is split along the longitu-

dinal center of the board to form two flaps 14 and 15 of sector shaped configuration, disposed with their meeting edges in overlapped relation. The two flaps are secured in pocket forming position by attachment 56 of the male and female members 16 and 17 respectively, of a fastener carried by the flaps.

Intermediate the ends of the cover, the body thereof is retained in position on the ironing board by means of opposed pairs of elastic straps 18 and 19 attached to the side edges of the cover strip and with each pair of straps converging at their free ends into webs 20 and 21; which webs carry the 55 component elements of a fastener 22. In service position, with the elastic straps secured by the fastener, the elasticity of the straps exerts a tension on the body of the cover, transversely of the ironing board, 60 insuring against wrinkling of the cloth.

In Figures 1 and 2, one position of the applied cover is illustrated. When desired the cover may be reversed, and the pocket portions at each end turned inside out, to 70 present a fresh ironing face for the cloth. This reverse, or inverted position is illustrated in Figure 3. As the elastic straps 18 and 19 are attached to the side edges of the cover, they may be fastened under the board 75 at all times. The flaps 14 and 15 permit application of the cover freely and quickly.

Claim.

A cover for ironing boards comprising 80 a cloth strip shaped to lie over the top of an ironing board, reversible board end engaging pockets attached to each end of said strip, one of said pockets being divided longitudinally of said strip, fastening members 85 carried by the portions of said divided pocket, and means for connecting the opposite side edges of said strip beneath an ironing board under tension.

SIGMUND F. KOHN,
